UNITED STATES PATENT OFFICE.

HENRY N. STAATS, OF CHILLICOTHE, OHIO.

SMOKING TUBE.

Application filed October 21, 1925. Serial No. 63,845.

This invention relates to new and useful improvements in smokers' articles, and particularly to devices for holding cigarettes and cigars.

5 The principal object of the invention is to provide a device of this character wherein the paper wrapper of a cigarette will remain comparatively intact, while the tobacco will be consumed therewithin.

10 Another object is to provide a device of this character wherein the ashes will be held against dropping on the clothes of the smoker, or being blown around by the wind, especially while the smoker is driving an automobile.

15 Another object is to provide a device of this character wherein the draft is induced through the center of the cigarette, thereby insuring the more rapid burning of the tobacco than of the wrapper, thus causing the said wrapper to retain the ashes within the device, and at the same time insuring the smoker against the injurious effects of the products of combustion of the paper wrapper.

20 Other objects and advantages will be apparent from the following description when taken in connection with the accompanying drawing.

25 In the drawing:

Figure 1 is an elevation of a smoking tube made in accordance with the present invention.

30 Figure 2 is an enlarged longitudinal central sectional view through the intermediate portion of the device, showing a cigarette therein, and said cigarette broken away.

35 Figure 3 is a perspective view of the cigarette holding tubular member removed from the mouthpiece.

40 Referring particularly to the accompanying drawing there is shown a noncombustible tube formed in two sections 10 and 11, by dividing the tube longitudinally. On one end of the section 10 there is formed a disk 12 which is tightly embraced by the adjacent end of the section 11, when the sections are in position to form the complete tube, while the other end of the section 11 is formed with a similar disk 13.

45 The disks 12 and 13 are each formed with a central draft opening 14, which, when a cigarette is properly enclosed within the tube, lies at the center of an end of the tobacco filler of the cigarette. Each of the sections 10 and 11 is formed with the series

50 of longitudinally extending slots 15, the extent of each of which is approximately one-half of the length of the tube. Projecting from the inner end of the section 11 is a pin 16, to which reference will be made later herein.

55 The mouthpiece 17 is of the conventional form, and has the metal ferrule 18 on its larger end for the reception of the pin carried end of the tube, and is formed with a curved hook 19 for engagement with said pin whereby to properly lock the tube within the ferrule. Within the ferrule is disposed a metal plate 20 having a central 60 opening 21, and surrounding the outer end of the opening is an outwardly projecting nipple 22 which, when the parts are properly assembled, and a cigarette is held within the tube, passes through the opening 14 65 of the disk 13, and into the center of the adjacent end of the tobacco filler of the cigarette.

70 The sections 10 and 11, of the cigarette holding tube, are movably connected together by the hinge means, which is formed by cutting the elongated slots 23 in the abutting edges of the sections, and engaging tubular metal members 24 therethrough and embracing the outer walls of the slots. 75

80 Attention is particularly called to the fact that the disks 12 and 13 are arranged at opposite ends of the device, whereby the opposite end of each of the sections is unobstructed. After the cigarette has been 85 completely consumed, the tubular member is removed from the mouthpiece and the sections swung into open position. The operator then grasps the mouthpiece and scrapes the remains of the cigarette from 90 the inner faces of the sections 10 and 11 by drawing the curved hook longitudinally within the sections. The remains of the cigarette are thus scraped through the unobstructed ends of the sections. 95

100 100 What is claimed is:

1. A smoking tube including an enclosing wall for receiving a cigarette, a mouthpiece receiving one end of the tube, and a nipple carried by the mouthpiece and disposed within the tobacco in the end of the cigarette.

105 110 115 2. A smoking tube comprising an enclosing wall including movably connected sections, an apertured disk in one end of the enclosing wall, a mouthpiece receiving one end of the tube, and means in the mouth-

piece for passage through the aperture of the disk and into the tobacco of a cigarette within said tube.

3. A smoking tube including an enclosing wall comprising movably connected sections, each section having a centrally apertured wall in one end for embracing engagement by the adjacent end of the other section, and a mouthpiece for supporting said tube.

4. A smoking tube including an enclosing wall comprising movably connected sections, each section having a terminal centrally apertured disk for embracing engagement by the adjacent end of the other section, a mouthpiece receiving one end of the tube, and means in the mouthpiece for passage through the opening of the adjacent disk

and into the tobacco of a cigarette within said tube.

5. A smoking tube including a cigarette containing receptacle having elongated slots and comprising hinged sections, each of the sections having a terminal centrally apertured disk for embracing engagement by the adjacent end of the other section, a mouthpiece having a ferrule for receiving an end of the smoking tube and having interlocking engagement therewith, and a nipple in the mouthpiece engaged through the adjacent apertured disk and into the tobacco of the adjacent end of a cigarette contained within said receptacle.

In testimony whereof, I affix my signature.

HENRY N. STAATS.
